UNITED STATES PATENT OFFICE.

CHARLES F. GEIGER, OF PERTH AMBOY, NEW JERSEY, ASSIGNOR TO THE CARBORUNDUM COMPANY, OF NIAGARA FALLS, NEW YORK, A CORPORATION OF PENNSYLVANIA.

MUFFLE FURNACE.

Application filed May 31, 1922. Serial No. 564,868.

To all whom it may concern:

Be it known that I, CHARLES F. GEIGER, a citizen of the United States, residing at Perth Amboy, county of Middlesex, State of New Jersey, have invented a new and useful Improvement in Muffle Furnaces, of which the following is a full, clear, and exact description, reference being had to the accompanying drawings, forming part of this specification, in which—

Figure 1 is a partial horizontal section on the line I—I of figure 2;

Figure 2 is a transverse vertical section; and

Figures 3 and 4 are perspective views of two forms of tile which I prefer to employ.

My invention relates to muffle furnaces wherein the material to be heated is out of contact with the combustion gases and particularly to a new and improved construction for the roof and side walls of the muffle chamber.

I will now describe my invention as applied to a muffle furnace, such as used in enameling of iron or steel or burning terra cotta, it being understood that it may be applied to any muffle furnace. In such a furnace, there is an internal closed chamber or muffle having substantially vertical side walls and an arched roof with spaces beneath the floor, around the sides, and above the roof of the muffle, for the circulation of combustion gases, the muffle being surrounded by an enclosing structure containing the combustion chambers. The combustion chambers are ordinarily beneath or adjacent to the floor of the muffle, and the gases after being discharged underneath the floor are led up through flues at the sides of the furnace between the outside and side walls, and thence along the roof between the outside and inside arches and then discharged. In all cases, the gases are closed off from the muffle chamber, since in this class of work it is necessary to keep the gases away from the articles being treated.

In the muffle furnaces, the wall of the muffle acts to isolate the atmosphere inside the muffle chamber from the combustion gases, and at the same time conduct heat from the gases into the chamber. It is desirable that the muffle walls should be thin, so that the greatest amount of heat may be transmitted, but it is difficult to obtain this object while

retaining the proper structural strength. 55 The roof of the muffle has ordinarily been made of slabs of a considerable thickness, necessary to give proper strength and bearing at the edges and provide proper stability.

In accordance with my invention, the side walls and arches of the muffle are formed of hollow tile, this being particularly important in the roof arch construction.

In the drawings, 2 represents the general 65 masonry structure of a muffle furnace containing a muffle of which the side walls are formed of hollow tiles 3, and the roof arch is also formed of hollow tiles 4. The end walls of these hollow tiles may be and preferably are provided with alternate projections and recesses 5 and 6, so that one row of tiles will interlock with the adjacent rows and give intersupporting of the rows. This, however, may or may not be used as desired. 70 The fire boxes indicated at 7 are preferably 75 staggered on opposite sides of the muffle chamber so that the gases of combustion from one side will pass through their flues around the muffle in a direction opposite to 80 those in the fire box on the opposite side. This compensating arrangement gives greater uniformity of temperature in the muffle because the hottest gases from one part of the furnace will heat a section next 85 adjacent to the part where the cooler gases from the opposite fire boxes pass.

In the form shown, the gases leaving the fire box divide, a portion of them passing through the flues 8 underneath the floor of 90 the muffle and up the side flue 9 to the exit flue 10, while the other portion passes up through the side flues 11, thence through the roof arch flues and to the other exit flue at 95 12. The exit flues are preferably provided with dampers 13, so that the flow of gases in either direction may be better controlled.

Instead of dividing the gases at the fire box, I may direct all the gases from the fire box up the side flue, over the top of the arch, down the other side flue and then back through the bottom flue to an exit flue adjacent the fire box.

The tiles are preferably made of bonded silicon carbide, as this gives greater structural strength and high thermal conductivity at high temperatures. For example, if I use a tile of a cross section of six inches in-

side dimensions, with the side walls of the tile one-half inch thick, I can obtain all the stability of a wall or arch six inches thick, and at the same time, obtain the conductivity 5 of a wall only one-half inch thick.

The advantages of my invention will be obvious to those skilled in the art, since a strong rigid muffle construction of high heat conductivity is afforded in a relatively 10 cheap and simple manner.

While I have shown the side walls and roof as composed of the hollow tile, this may be varied. For example, I may substitute flues along the side walls, each flue 15 being in the form of a pilaster composed of hollow tiles, and thence being carried across and under the roof of the muffle in the form of an arch. This will give a larger radiating surface from the tile into the muffle, 20 since the roof tiles will be in the muffle chamber. Again, instead of the self-supporting arches of square or rectangular tiles, as shown, I may employ cylindrical tiles, or tiles of other cross sectional shape, each arch 25 being a self-supporting unit. These arches may be laid close together, whether interlocked or not, or may be spaced apart, if desired.

The furnace may be used for many purposes, and other changes may be made without departing from my invention.

I claim:

1. In a muffle furnace, a muffle having in its roof hollow tiles forming a self-supporting arch and arranged to form a flue for products of combustion, said tiles being of uniform thickness throughout their length and joined together end-to-end without overlapping portions.

40 2. In a muffle furnace, a muffle having its roof portion formed of hollow tiles forming

a self-supporting arch comprising a plurality of flues, and means for directing combustion gases through the flues formed by said tiles, said tiles being of uniform thickness throughout their length and the tiles in each flue being joined together end-to-end without overlapping portions. 45

3. In a muffle furnace, a muffle having its roof portion formed of hollow tiles forming a self-supporting arch and constructed and arranged to form a plurality of interlocking flues, and means for directing combustion gases through the flues formed by said tiles. 50

4. In a muffle furnace, a muffle having its side walls formed of superimposed hollow tiles forming a flue for combustion gases, said tiles being of uniform thickness throughout their length and joined together end-to-end without overlapping portions. 55

5. In a muffle furnace, a muffle having its side walls and roof containing combustion flues formed of hollow tiles, the tiles of the roof forming a self-supporting arch, said tiles being of uniform thickness throughout their length and the tiles in each flue being joined together end-to-end without overlapping portions. 60

6. A muffle furnace having its side walls formed of hollow tiles constructed and arranged to form a plurality of interlocking flues, and means for directing combustion gases through the flues formed of said tiles. 65

7. A muffle furnace having the muffle with its side walls and roof formed of hollow tiles forming flues for combustion gases, the rows of tiles interlocking with each other.

In testimony whereof I have hereunto set 70 my hand.

CHARLES F. GEIGER.
